DUAL BURNER CIRCULATING HEATER

Paul D. Kilbury, Hawthorne, Calif.

Application July 17, 1959, Serial No. 56,831

Term of patent 14 years

(Cl. D81—1)

Fig. 1.

Fig. 2.

Fig. 3.

Fig. 4.

Fig. 5.

Fig. 1 is a front elevational view of a heater showing my new design;

Fig. 2 is a back elevational view;

Fig. 3 is a right side elevational view;

Fig. 4 is a left side elevational view; and

Fig. 5 is a top plan view.

The dominant features of my design reside in the portions shown in full lines. Portions of the elements shown in the broken lines in Figs. 1 and 2 are broken away for convenience of illustration.

I claim:

The ornamental design for a dual burner circulating heater, as shown and described.
